UNITED STATES PATENT OFFICE.

AUGUST THONET, OF VIENNA, AUSTRIA-HUNGARY, ASSIGNOR TO THONET
BROTHERS, OF SAME PLACE.

DESIGN FOR A CHAIR.

SPECIFICATION forming part of Design No. 22,023, dated November 29, 1892.

Application filed June 22, 1892. Serial No. 437,659. Term of patent 7 years.

To all whom it may concern:

Be it known that I, AUGUST THONET, a citizen of the Empire of Austria-Hungary, residing at Vienna, in the Empire of Austria-Hungary, have invented and produced a new and original Design for Chairs, of which the following is a specification.

This invention relates to a design for a chair in which arched backwardly-curved rounds are arranged between the upwardly-extended hind legs.

The nature of my design is clearly shown in the accompanying drawing, which represents a perspective view of the chair.

In the drawing, A represents the seat, B the hind legs, which are extended in upward direction above the seat, and C C are arched

and backwardly-curved rounds that extend between the upper extensions of the hind legs and impart thereby a peculiarly-striking yet ornamental appearance to the same.

Having thus described my invention, I claim as new and desire to secure by Letters Patent—

The design for a chair, substantially as herein shown and described.

In testimony that I claim the foregoing as my invention I have signed my name in presence of two subscribing witnesses.

AUGUST THONET.
